UNITED STATES PATENT OFFICE.

MICHAEL G. DELANEY, OF SYRACUSE, NEW YORK, ASSIGNOR OF THREE-
FOURTHS TO ISRAEL COBE, OF NEW YORK, N. Y.

NON-REFILLABLE BOTTLE.

SPECIFICATION forming part of Letters Patent No. 783,625, dated February 28, 1905.

Application filed May 5, 1904. Serial No. 206,519.

To all whom it may concern:

Be it known that I, MICHAEL G. DELANEY, of Syracuse, in the county of Onondaga, in the State of New York, have invented new and useful Improvements in Non-Refillable Bottles, of which the following, taken in connection with the accompanying drawings, is a full, clear, and exact description.

This invention relates to the class of bottles which are provided with means for preventing the same from being refilled.

The object of this invention is to produce a bottle which shall be very simple in construction, efficient in its use, and at the same time shall be inexpensive to manufacture; and it consists in the novel construction and arrangement of the component parts, as hereinafter fully described, and set forth in the claims.

In the accompanying drawings, Figure 1 is a longitudinal section of a portion of a bottle embodying my invention. Figs. 2, 3, and 4 are transverse sections on lines X X, Y Y, and Z Z, respectively, in Fig. 1; and Fig. 5 is a detail side view of the liquid-conducting cone applied to the interior of the neck of the bottle.

Referring to the drawings, A denotes the body of the bottle, which is formed with the usual neck B, both of which may be of any suitable style. The lower portion of the neck 30 is provided with an internal circumferential shoulder or rib a, and the upper portion of said neck is provided with an internal circumferential groove b.

C represents a metallic tube which is fitted closely to the interior of the neck and bears with its inner end upon the said shoulder a. This tube may be formed from any suitable non-corrosive metal which will permit the same to be expanded to produce an external bead c, 40 engaging the aforesaid groove b in the neck, and thereby permanently lock the tube in the neck. To effectually guard against malicious removal of the tube by the insertion of a tool or instrument between the outer end of tube 45 and neck, I provide the interior of the neck with a circumferential shoulder d above the groove b, against the under side of which shoulder the outer end of the tube abuts, as shown in Fig. 1 of the drawings.

D represents a hollow truncated cone 5° through which the liquid is conducted when discharged from the body of the bottle. Said cone is disposed centrally within the tube C and with its smaller end extending toward the mouth of the neck and is rigidly secured at its inner or larger end to the inner end of said tube in any suitable manner. The cone is also composed of suitable non-corrosive metal and preferably bears upon the aforesaid shoulder a in the neck. The said cone D is provided in one side, preferably at outer end, with an outlet-opening e, which end is closed by means of a transverse plate f, which has a portion of its edge contiguous to the tube C and is arranged with a passage g between the plate and tube, which passage is disposed at the opposite side of the cone. The contiguous edge of the said plate is provided with air-ports f' f'. In the inner end of the cone D is rigidly secured a plug d', provided with a central port a', through which the liquid is discharged, and in the outer face of this plug and surrounding the port is provided a concave valve-seat h', in which is normally disposed a semispherical valve i'. Said valve is pivotally connected to 70 the plug, preferably by means of an ear d', formed thereon, which is inserted between similar ears e' e', and a pin passing through said ears, which latter ears project from the top face of the plug, as more clearly shown in Fig. 3 of the drawings. The aforesaid plate f is arranged over the outlet-opening e of the cone and constitutes a guard serving to prevent the introduction of an instrument through the opening and thereby tampering with the valve.

f² represents a weight loosely suspended from the valve and which is fastened to a rod g', which is provided with a cross-bar h', engaging an eye or loop i', formed on the lower end of the stem i, depending from the valve. Said weight serves to insure the closing of the valve, and the cross-bar coming in contact with the under side of the plug serves as a stop limiting the opening movement of the valve. When the bottle is in its tilted position and attempt is made to force liquid into the same, the described loose connection of

the weight and valve allows the latter to close independent of the weight.

The lower portion of the aforesaid cone D is provided with small air-ports b^2 b^2 . These 5 air-ports, in connection with the aforesaid air-ports f^2 f^2 , serve as vents to facilitate the discharge of the liquid.

A represents the cork, (shown in dotted lines,) which is inserted into the mouth of the 10 bottle in the usual manner.

What I claim as my invention is—

1. In a bottle of the class specified, the combination with the neck, of a hollow liquid-conducting cone rigidly secured therein and disposed with its smaller end extending outward and provided in one side near said end with an outlet-opening, a transverse guard-plate secured to said end of the cone and partly closing the neck to form a passage between the 15 opposite side of the cone and neck, and a valve controlling the discharge of liquid from the body of the bottle into the cone as set forth.

2. In a bottle of the class specified, the combination with the neck, of a hollow liquid-conducting cone rigidly secured therein and disposed with its smaller end extending toward the mouth of the bottle and provided in said end with an outlet-opening and having a guard above said opening, a plug secured in the inner 25 end of the cone and provided with a discharge-port and in its outer face with a concave valve-seat surrounding said port, and a semispherical valve hinged to the outer face of the plug and adapted to enter said seat, 30 and a weight suspended from said valve as set forth.

3. In a bottle of the class specified, the combination with the neck, of a liquid-conducting cone rigidly secured therein and provided with 35 an outlet-opening, a guard above said opening, a hinged valve in the inner end of the cone and provided with depending stem formed at its free end with an eye, and a weight provided with a rod formed with a cross-bar by 40 which it is loosely suspended from said stem for the purpose set forth.

4. In a bottle of the class specified, the combination with the neck provided with an internal circumferential shoulder at its lower portion, of a tube fitted tightly to the interior 45 of the neck and seated upon said shoulder, a hollow liquid-conducting cone secured at its larger end in the inner end of said tube and provided in one side near its smaller end with

an outlet-opening and provided with a guard 55 over said opening, a plug secured in the larger end of the cone and provided with a discharge-port and with a concave valve-seat surrounding said port, and a semispherical valve adapted to enter said seat and hinged to the outer 60 face of the plug as set forth.

5. In a bottle of the class specified, the combination with the neck, of a tube permanently locked to the interior thereof, a hollow liquid-conducting cone rigidly secured at its larger 65 end in the inner end of the tube and provided in one side with an outlet-opening, a transverse guard-plate secured to the outer end of the cone and arranged with a passage between the plate and tube at the side opposite the outlet of the cone, and a valve disposed in the larger end of said cone as set forth.

6. In a bottle of the class specified, the combination with the neck provided with an internal circumferential groove, of a metallic tube 75 fitted to the interior of said neck and formed with an external bead engaging said groove and permanently locking the tube to the neck, a hollow liquid-conducting cone disposed with in the tube with its smaller end extending outward and provided therewith an outlet-opening, and rigidly secured at its larger end to the inner end of the tube, a guard secured to the outer end of the cone over said opening, a plug secured in the larger end of the 80 cone and provided with a discharge-port and with a concave valve-seat in its outer face and surrounding said discharge-port, and a weighted semispherical valve hinged to the plug as 85 set forth.

7. In a bottle of the class specified, the combination with the neck, of a hollow liquid-conducting cone rigidly secured therein with its smaller end extending outward and provided in one side with an outlet-opening and with a 95 transverse guard-plate on said end disposed over the opening and having air-ports at its edge, said guard-plate arranged with a passage between it and the neck, the cone having air-ports in one side at its lower portion, and a valve controlling the discharge of liquid 100 from the body of the bottle into said cone as set forth.

MICHAEL G. DELANEY.
